CLAIM

The ornamental design for a tool for fixing a tension member of composite strand for prestressed concrete reinforcement and post tensioning concrete structure, as shown and described.

DESCRIPTION

FIG. 1 is a front, bottom and left side perspective view of an embodiment of a tool for fixing a tension member of composite strand for prestressed concrete reinforcement and post tensioning concrete structure, showing our new design; FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof;

FIG. 8 is an enlarged sectional view thereof; taken along line 8-8 in FIG. 2;

FIG. 9 is an enlarged sectional view thereof; taken along line 9-9 in FIG. 2; and,

FIG. 10 is a perspective view showing the state of use thereof.

The broken lines in the drawings illustrate portions of the tool for fixing a tension member of composite strand for prestressed concrete reinforcement and post tensioning concrete structure and form no part of the claimed design. The broken line showing of the cable in FIG. 9 illustrates the environment of the claimed design and forms no part

(Continued)

thereof. The dot-dash-dot broken lines in the drawings define the bounds of the claim and form no part thereof.
